Des. 635

Isaac De Grouche, of Troy, N. Y.
(Assignor to Louis Potter, of the same place.)
Letters Patent No. 635. Dated 14th March, 1854.

The Schedule referred to in these Letters Patent, and making part of the same.

To all whom it may concern:—

Be it known, that I, Isaac De Grouche, of Troy, in the county of Rensselaer, and State of New York, have invented, or produced, a new and original design of Panel Ornament for Stoves, &c. and I do hereby declare that the following is a full, clear, and exact description of the same, reference being had to the annexed Drawing, making a part of this Specification:—

The design of my panel ornament consists of the flowers and stem (a, a), leaves (b, b), shells (c, c), and center piece (d), combined and arranged for the purpose of a panel ornament, as shown in the Drawing. Having thus described my Design of Panel Ornament, what I claim as new, and desire to secure by Letters Patent is, the ornamental configuration and arrangement of the parts herein described, constituting a panel ornament, as represented in the drawing hereto annexed.

Isaac De Grouche.
